(57) **CLAIM**

The ornamental design for a pole for automotive cleaning device, as shown and described.

DESCRIPTION

The present application claims priority to Applicant's co-pending U.S. patent application Ser. No. 12/099,645, filed Apr. 8, 2008, incorporated herein by reference.

FIG. 1 is a perspective view of a pole for an automotive cleaning device showing the new design, the portions shown in phantom being for environmental purposes only and forming no part of the claimed design;

FIG. 2 is a top plan view thereof;

FIG. 3 is a side elevation view thereof, the opposite side being a mirror image;

FIG. 4 is a bottom plan view thereof;

FIG. 5 is an end elevation view thereof; and,

FIG. 6 is a front elevation view thereof.

The pole for automotive cleaning device is shown enlarged and broken away in FIGS. 2-4 so that the enlarged scale drawings can fit on the page.
